UNITED STATES PATENT OFFICE.

GEORGE W. BEAN, ARAUNA M. VAIL, AND STEPHEN A. VAIL, OF PHILADELPHIA, PENNSYLVANIA.

DESIGN FOR A PERFUMERY-HOLDER, &c.

SPECIFICATION forming part of Design No. 19,292, dated September 3, 1889.

Application filed June 10, 1889. Serial No. 313,745. Term of patent 3½ years.

To all whom it may concern:

Be it known that we, GEORGE W. BEAN, ARAUNA M. VAIL, and STEPHEN A. VAIL, citizens of the United States, residing in the city 5 and county of Philadelphia, State of Pennsylvania, have invented and produced a new and original Design for a Perfumery Holder or Stand, of which the following is a specification, reference being had to the accompanying drawings, forming part thereof.

The leading feature of our design for a perfumery holder or stand is a tripod with a spherical bottle depending therefrom, said bottle having a figure of a fish therin.

15 In the drawings, A designates a tripod with a hanger B. Depending from the hanger is a spherical bottle C, within which is a figure D, simulating an aquarium.

We claim—

The design for a perfumery-holder, substantially as herein shown and described.

GEORGE W. BEAN.
ARAUNA M. VAIL.
STEPHEN A. VAIL.
